UNITED STATES PATENT OFFICE

WATSON H. WOODFORD, OF BRIDGEPORT, CONNECTICUT, ASSIGNOR TO REMINGTON ARMS COMPANY, INC., A CORPORATION OF DELAWARE

MANUFACTURE OF PAPER TUBES

Application filed July 5, 1927. Serial No. 203,445.

This invention relates to the manufacture of articles of paper and other fibrous material, and will be described with particular reference to the manufacture of shot shells, 5 although many aspects of the invention are applicable to the manufacture of other articles.

In the manufacture of shot shells, tubes for the shell bodies are formed by winding 10 a sheet of paper about a mandrel, the completed tube comprising about four and one half layers of paper. An adhesive such as starch is usually applied to the surface of the paper as it is wound, the rolled tubes are 15 then stripped from the mandrel and are subjected to various treatments for the purpose of rendering them somewhat impervious to moisture and also protecting them from burning or charring under the heat generated by the combustion of the shot propellant powder.

The methods hitherto in vogue have involved dipping the tubes in molten paraffin wax. The paraffin, absorbed by the inner 20 layers of the paper, acted as a heat absorbent, tending to keep the temperature of the paper below its charring point during the firing of the shell, and it also acted in a measure to prevent the absorption of moisture. Serious disadvantages, however, attend the use of paraffin. The starch adhesive repels it, so that it was necessary to remove all or nearly all of the starch applied to the two inner layers of paper in order to 25 permit the absorption of a sufficient quantity of paraffin to prevent charring. Another defect arises from the fact that paraffin itself does not render the tubes waterproof. Attempts to apply waterproofing varnishes 30 or lacquers have been unsuccessful owing to the peculiar reaction between paraffin wax and the solvents ordinarily used in spirit varnishes and lacquer. When such a varnish or lacquer is applied over paraffin wax 35 the drying of the varnish is delayed indefinitely. A part of the surface may dry but a substantial fraction remains soft and tacky for an indefinite time. The reaction seems to be as follows: Paraffin is dissolved in the 40 varnish solvent, and quickly reaches the sur-

face. As a small quantity of the paraffin laden solvent evaporates the precipitated paraffin forms an impervious film over the wet varnish and prevents further evaporation of the solvent. If this film is broken, 55 permitting the solvent to evaporate, the varnish may dry, but the surface is substantially a paraffin surface rather than a varnish surface.

Other water-proofing agents such as polymerizable oils, have been used with a measure of success, but are not entirely satisfactory. One cause of their failure may be found in the fact that the adhesive starch repels such oils, and it being impracticable 60 to keep the outside of the tube free from starch, only an imperfect and broken coating of the polymerizable oil can be secured.

It is an object of the present invention to construct a finished article such as a shot 65 shell which will be quite impervious to moisture and will at the same time be proof against any undesirable charring from high heat in its interior.

A further object of the invention is to 70 provide articles such as paper tubes for shot shell bodies which while being substantially fire-proof will have a surface which is free from greases, waxes and oils.

A further object of the invention is to 75 provide a paper tube having interior layers which are treated with a heat absorbent substance, and other layers which are free from said substances.

A further object of the invention is to 80 construct a shot shell capable of receiving a coat of varnish or lacquer.

A further object of the invention is to 85 devise a method of applying varnish, lacquer or other water-proofing medium to the body 90 of the shot shell in such a way as to form a varnish film which is continuous over the shell body, the crimp and the top wad.

A further object of the invention is to 95 provide means and a method for effectively sealing the end of the crimp against penetration by moisture.

With these and other objects in view, the invention consists in the novel devices and methods of procedure, of which the methods 100

and the devices herein to be described may be considered as typical.

In the drawings:

Fig. 1 is a fragmentary plan view of a sheet of paper prepared for winding according to the methods of the present invention.

Fig. 2 is an elevation of a finished shot shell comprising a tube wound from paper prepared as illustrated in Fig. 1, the wall of the tube being broken in such a way as to show its construction.

Fig. 3 is an enlarged section through the wall of a tube wound from such a sheet of paper as is shown in Fig. 1.

Fig. 4 is a fragmentary sectional view, showing the top wad and crimp of a shot shell water-proofed in accordance with one method of practicing the present invention.

Fig. 5 is a fragmentary plan view of a sheet of paper treated according to an alternative method of practicing the invention.

Fig. 6 is an enlarged section through the wall of a tube constructed from such a sheet as is shown in Fig. 5.

Fig. 7 is an enlarged sectional view of a tube wall modified slightly from Fig. 6.

In order to provide that a part at least of the juxtaposed surfaces of the paper in the wound tube shall be free from any substances which will interfere with the proper action of the adhesive, and that the outer layer shall be free from any substance which will adversely affect varnish or lacquer, while at the same time the tube is protected from undesirable and dangerous charring, the invention contemplates treating a part only of the tube material with a heat absorbent substance. This substance, which is conveniently applied to the tube forming paper before winding, must be of such a nature that it can be applied to the desired part of the paper, while other parts of the paper are left and permanently remain free from the substance. It must also have a high specific heat thereby enabling it to absorb such a quantity of heat that the temperature of the paper will not be raised to its charring point. It has been found that petrolatum or compositions including substantial amounts of petrolatum satisfy these requirements.

Fig. 1 illustrates a portion of a sheet prepared for winding by treating an intermediate section with petrolatum. A portion 10 of the sheet adjacent one end and having such a width as to form a little more than one complete layer on the interior of the wound tube is left free from petrolatum. Adjacent to this untreated portion 10 is an intermediate section 11, having such a width as to furnish about two complete layers in the tube, well impregnated with petrolatum. The remaining portion 12 of the sheet which forms slightly more than one layer on the

outside of the tube is also left untreated. One side of this part of the sheet may be colored if desired according to the usual practice.

Fig. 2 illustrates a shot shell comprising a tube wound from the sheet shown in Fig. 1; the shell comprising the inside untreated layer or wrap 10, the intermediate treated layers 11, and the exterior untreated layer 12. The dry or untreated sections of the paper forming respectively the inside and outside of the tube each overlap slightly providing juxtaposed dry surfaces adjacent the margins of the paper insuring the adhesion of the margins necessary to prevent unwinding or separation of the layers. The oil free exterior surface layer 12 is adapted to receive a coating of varnish or lacquer 13.

The properties of the impregnating material as well as the qualities of the sheet and the tubes rolled therefrom may be controlled by adding other substances to the petrolatum. For example, penetration of the paper is increased by the use of about 10% of stearic acid. These and similar impregnating materials may obviously be utilized according to the methods which have been outlined or otherwise in the manufacture of tubes which are wound dry as well as in the making of tubes from sheets moistened with starch solution.

The invention further contemplates water-proofing by the use of varnish, lacquer or similar materials, and the application of the water-proofing by a method adapted to rapid production, and the packing of the shells within a short time after the application of the waterproofing. The water-proofing material may be a quickly drying spirit varnish, pyroxylin lacquer, or pyroxylin resin lacquer, such, for example, as a varnish comprising "Cumar", "Lindol", rape seed oil, celluloid and/or low viscosity pyroxylin, dissolved in acetone, methyl alcohol, amyl acetate, ethyl acetate or benzine. Any such varnish or lacquer will, for the purpose of this application, be identified as "lacquer varnish".

The invention further contemplates the application of the lacquer varnish in such a way as to insure the water-proofing not only of the periphery of the shell body but also of the top wad and crimp. To this end, shells are dipped in the inverted position shown in Fig. 2. After dipping, the shells are retained in the inverted position during drying, the excess lacquer varnish draining from the end of the shell adjacent the crimp. In this operation a fillet of lacquer varnish 14 (Fig. 4) is formed in the angle between the shell crimp 15 and the top wad 16, and retained there during the drying by surface tension. By this means the most vulnerable part of the shell body, namely the joint be-

tween the top wad and the crimp is effectively sealed by a heavy and impervious coating. The top wad is coated and water-proofed in the same operation, the lacquer varnish penetrating the wad to a certain extent, as shown in Fig. 4. This method of water-proofing is, of course, applicable to any shot shells or other articles having a surface adapted to receive varnish, and is not limited to shot shells constructed according to the methods above set forth.

It will be seen that the finished shell is completely sealed by a continuous coat of varnish which is applied to and dries simultaneously on all parts of the shell. A positively water-proof article is thus secured. Shells prepared and treated in this way have been submerged in water for a period of 24 hours, and at the end of such period showed no undesirable swelling. Shells water-proofed according to the best methods hitherto used have been incapable of resisting penetration by moisture when submerged for periods of four or five hours. Applicant's shells, moreover, are free from undesirable or dangerous charring of the paper during firing. The interior layer of paper, if untreated, may show local charring, but the charring is effectively stopped by the treated or coated layers so that the shell body is not appreciably weakened, and no sign of charring reaches the exterior surface.

Figs. 5, 6 and 7 illustrate an alternative form of the invention. The paper sheet shown in Fig. 5 has secured to an intermediate section thereof a strip of metal foil. As shown, the metal foil is of such width as to form one complete layer in the wound tube. In Figs. 5 and 6 three layers of paper 100, lie within the metal foil bearing layer and one layer 120 is placed outside the metal foil. This arrangement, however, may be varied. Thus Fig. 7 shows the metal foil between the second and third layers of paper. In either case, the charring of the paper is positively stopped by the metal foil, and the tube is entirely free from any greases, waxes or oils having a deleterious effect on lacquer varnish. Shot shells comprising tubes made from such sheets may thus be waterproofed by the application of lacquer varnish according to the method above disclosed with excellent results. This method in the manufacture of shot shells has been made the subject of my co-pending application Serial #204,845 filed July 11th, 1927.

The representative embodiments and methods of practicing the invention which have been described herein are to be considered as illustrative rather than restrictive, the invention being susceptible of many modifications both as to materials and de-

tails of the method of procedure, all falling within the scope of the appended claims:

What is claimed is:

1. In the manufacture of paper shot shells, the method of controlling charring of the paper under the heat of firing the shell which comprises the application of petrolatum to the shell. 70

2. The method of making a waterproof and charproof shot shell which comprises the application of a heat absorbing material to an interior portion only of the wall of the shell and the application of lacquer varnish to the exterior of the shell. 75

3. The method of making a waterproof and charproof shot shell which comprises the application of petrolatum to a portion of the wall of said shell, and the application of a lacquer varnish to the exterior of said wall. 80

4. A shot shell tube having a portion of its wall impregnated with petrolatum. 85

5. A paper shot shell having an interior portion of its wall impregnated with petrolatum, and a coating of lacquer varnish upon its exterior surface. 90

6. In the manufacture of paper tubes for shot shells the method of protecting the tube against charring which comprises applying a heat absorbing material to a portion of the paper from which the tube is to be wound 95 and then winding the tube.

7. In the manufacture of paper tubes for shot shells the method of protecting the tube against charring which comprises applying petrolatum to a portion of the paper from which the tube is to be wound and then winding the tube. 100

8. The method of making a paper shot shell waterproof and protected against charring which comprises applying a heat absorbing material to the paper from which the tube is to be wound then winding the tube and then applying a lacquer varnish to the wound tube. 110

9. The method of making a paper shot shell waterproof and protected against charring which comprises applying petrolatum to the paper from which the tube is to be wound then winding the tube and then applying a lacquer varnish to the wound tube. 110

10. A wound paper shot shell tube having an intermediate layer of the tube treated with a heat absorbing material, the innermost and outermost layers of the tube being untreated with said material. 115

11. A wound paper shot shell tube having an intermediate layer of the tube treated with petrolatum, the innermost and outermost layers of the tube being untreated with said petrolatum. 120

12. In a wound paper tube for shot shells the combination of petrolatum applied to an inner wrap of the tube and a waterproofing lacquer varnish applied to the outer surface of the tube. 125

13. A paper shot shell tube protected from charring by petrolatum applied to an intermediate layer of the tube.

14. A wound paper shot shell tube protected from charring by a heat absorbing material applied to an intermediate layer only of the tube.
